In Sweden May 19, 1943

6 Claims. (Cl. 235—62)

1

This invention relates to calculating machines and more particularly to multiplying machines having an actuator to be operated in two directions, that is the + direction and the - direction. It may be applied, for instance, to pin wheel or Odhner machines.

The chief purpose of this invention is to simplify the mechanism for automatic shifting in operations of multiplication.

Another purpose of this invention is to get the necessary shifting impulses in such machines with automatic shifting in a manner more simple and more reliable than heretofore, especially when the machine is also capable of automatic division.

Another purpose is to render it possible to depress the operation keys more easily by the finger.

Another purpose of this invention is to create a direct and positive disengagement of the driving mechanism, that is of the motor coupling, without the use of any springs.

Another purpose of this invention is to render the machine more reliable and less sensitive to shocks and rough handling; in other words the risk of machine faults is essentially reduced. This is of course most important in rapidly operating calculating machines driven by electric motors.

When not otherwise expressly stated, the expressions "right," "left," "upwards," "downwards," "forwards," "backwards," "front" and "back" are used in this specification and in the claims as such directions appear to an operator sitting at the key-board of the machine to manipulate it.

One embodiment of an improved calculating machine in accordance with this invention is illustrated in the annexed drawings.

Fig. 1 shows a section on the line I—I of Fig. 2 and is substantially an end view from the right side of the machine, with the right end plate removed.

Fig. 2 shows a front view of the upper part of the driving mechanism proper.

Fig. 3 shows a detail view of the stop discs, as viewed from above.

Fig. 4 shows a top view of the driving mechanism proper.

Fig. 5 shows an end view of certain details immediately to the left of the driving mechanism proper.

Fig. 6 is a cross-sectional view taken on the line VI—VI of Fig. 1.

Fig. 7 is a cross-sectional view taken on the line VII—VII of Fig. 1, showing a guiding plate.

2

Fig. 8 is a plan view of a part of the stop disc, and is taken on the line VIII—VIII of Fig. 3.

Fig. 9 is a cross-sectional view taken on the line IX—IX of Fig. 8.

Fig. 10 shows a plan view of one of the buffer discs in the stop disc mechanism.

Fig. 11 shows an end view of the clearing mechanism and the parts cooperating therewith.

Fig. 12 shows a detail (a side view) of the setting arm for setting the machine to direct subtraction, together with the parts cooperating therewith.

Fig. 13 shows a side view of the multiplication key.

15 Fig. 14 shows a side view of the member for holding down the multiplying and division keys (key holding-down lever).

Fig. 15 shows a top view of some control members arranged below the bottom plate on the machine.

Fig. 16 shows a top view of the driving transmissions and

Fig. 17 is a cross-sectional view on the line XVII—XVII of Fig. 16.

25 For the sake of clearness, only the essential parts are shown in the various figures.

The machine illustrated in the drawings is in its essential features constructed in accordance with U. S. Patents No. 2,108,596, No. 1,927,771, No. 30 2,243,075 and No. 2,398,286, though the invention by no means is limited thereto. See also U. S. Patent No. 2,431,930 and U. S. patent applications Nos. 532,461 (Patent No. 2,403,361 dated June 2, 1946) and 534,453 (corresponding respectively to 35 British Patents Nos. 574,000 and 575,100).

The machine illustrated in the drawings is of the Odhner or pin wheel type and has an actuator or pin wheel rotor R (Fig. 16) arranged in a carriage shiftable along the main shaft 58. For 40 carrying out the calculating operations this shaft together with the actuator R is rotated in either direction of rotation, that is + or - direction, being counterclockwise and clockwise, respectively, in Fig. 1; see arrows.

45 A shaft 10 is driven by a motor M and carries a gear 11 driving a gear 12a, which together with another gear 12b (Figs. 1, 4 and 16) is secured to a shaft 13. The gear 12a drives directly a gear 14, while the gear 12b drives a gear 15 through an 50 intermediate gear 17. The two gears 14, 15 are freely journaled on the shaft 16 and consequently they always rotate in opposite directions as long as the motor runs. Either of these gears 14 or 15 may be coupled to the shaft 16 by means 55 of the coupling pawl 18, which is rockable on a

pin 19a. This pin extends at right angles to the shaft 16, and is secured in the block 19 rigidly attached to the shaft 16 and passes through a slot in said block. Said slot is parallel with the shaft 16 and in it the pawl 18 is thus journalled. When said pawl is rocked in one direction or the other, its lateral projections will engage shoulders or offsets 20 (Figs. 16 and 17) on the sides of the gears 14 and 15, respectively. This couples the shaft 16 to the gear 14 or 15, respectively, that is, the shaft 16 is rotated in one direction or the other, because the gears 14 and 15 rotate in opposite directions. By means of the gears B the shaft 16 is in permanent driving connection with the main shaft 58 of the machine, which carries the actuator R. Thus, the actuator is rotated in the + direction or the - direction according as the pawl 18 is coupled to the toothed wheel 15 or 14, respectively.

For guiding the pawl 18 to engage and to disengage the shoulders on the gears 14 and 15, said pawl has a point or head at that end which is most remote from the pin 19a. This point enters a guiding slot 21a having oblique entrance edges 21b. This slot is cut in a movable guiding member 21 (Figs. 1, 2 and 7), and the point of the pawl 18 is in the guiding slot 21a, when the shaft 16 is at rest, that is when the actuator is in its full cycle position. When the shaft 16 rotates, the point of the pawl 18 engages one side or the other of a stationary arcuate guiding rail 22 (Fig. 1). Thus, the pawl 18 is positively guided during that part of the rotation of the shaft 16 during which the point of the pawl is outside of the slot 21a. The guiding rail 22 is preferably resiliently suspended. In other words, the slot 21a and the rail 22 together guide the pawl 18 during the whole revolution of 360°. Normally, the guiding member 21 with its guiding slot 21a is in its middle or central position (Fig. 7) and then the pawl 18 is disengaged from the shoulders 20. When in the manner stated below the guiding member 21 is moved to either side, it rocks the pawl 18 correspondingly to engage the corresponding shoulder on the gears 14 or 15.

A rocking arm 23 is pivotally journalled on the stationary pin 24 and one end 23a (Figs. 1 and 4) of it enters the space between two cam discs 25 and 26, which are secured to the shaft 13 and consequently rotate, when the motor runs. This swings the arm 23 to and fro with a reciprocating or pendulous motion on the pin 24. The opposite end of this arm has a recess 27 (Fig. 2).

Two coupling rods 28 and 29 are displaceably journalled on pins 30 (Figs. 1 and 2) secured to the stationary plate (frame part) 31 and entering oblong slots in the rods. Said rods may, therefore, be displaced in their longitudinal direction, and springs 32 are tensioned between said rods and stationary pins 33 and tend to lift the rods to their uppermost position. At their upper ends, these rods carry pins 34 entering slots 35 of an angular piece 36 which is displaceable laterally, that is parallel with the shaft 16, on a stationary shaft 37 (Figs. 1 and 7) secured between the two intermediate walls 38 and 39 of the machine frame. The angular piece 36 is rigidly connected with the guiding member 21 to form a rigid unit, normally kept in its central position between the walls 38 and 39 by a spring 40, as shown in Fig. 7. When the angular piece 36 and the guiding member 21 are in this central position, the pawl 18 is disengaged from the shoulders 20, as mentioned above. The angular piece 36 has a projection 41

(Figs. 1, 2 and 4), which rests against the inside of the downwardly projecting part (tab) 42 of the locking arm 43. At one end said locking arm is rotatably journalled on the pin 44 which is secured to a bent part (tab) on the side wall 38. A similar tab carries the pin 24. The opposite (outer) end of the locking arm 43 is embraced by the fork-shaped upper end of an arm 45 which is rotatably journalled on the pin 46 on the side wall 39 and is pressed by a spring 47 in such direction (clockwise in Figs. 1 and 11) that the part 42 engages the projection 41.

A pin 48 (Figs. 1, 2 and 6) is riveted to the angular piece 36 and enters the space between two double-conical pins 49 and 50. The pins 49 and 50 may also be described as having the shape of hyperboloids of rotation. These pins are riveted to the back ends of stopping pawls 51 and 52, respectively, rotatably journalled on a pin 53 secured to the side wall 39. Around this pin a torsion spring 501 is wound, acting upon the two stopping pawls so that the double-conical pins 49, 50 are pressed towards each other to engage the pin 48.

When the machine is at rest and no operation of calculation is being carried out, the two stopping pawls 51 and 52 engage their respective stopping shoulders 54 and 55 of two buffer discs 56 and 57 (Figs. 1, 3, 10 and 11), said torsion spring 501 pressing the points of the pawls inwards against the periphery of said buffer discs which are rotatably journalled on the main shaft 58 of the machine, which shaft carries the actuator R. Between the two discs 56 and 57 a strong buffer spring (compression spring) 59 is arranged which presses those discs to engage an eccentric bushing or sleeve 60 (Figs. 1, 3, 8 and 9). This bushing is either itself non-circular, for instance, oval or elliptic in cross-section, or is eccentrically journalled on a screw or stud bolt 61 which is secured for instance riveted to a cam disc 62 rigidly connected with the main shaft 58. On the screw 61 a nut 63 is screwed keeping the bushing 60 in its angular position as set on the screw 61. It is to be observed that the cam disc 62 is eccentrically arranged on the main shaft 58 and the circular slot 64 cut in said disc is consequently eccentric in relation to the main shaft 58. A roller 65 (Figs. 1 and 5) enters said slot and is journalled on a three-armed lever or release arm 310 which is pivoted on the stationary pin 67. The horizontal arm 66 of said lever extends inwards through the space between the rods 28 and 29 (Figs. 1 and 2) to engage the edges 68 of said rods from above. At this place the arm 66 is broadened so that it can cooperate with the edges 68 of both rods 28 and 29, as is shown in Fig. 2. To the lower arm of the release lever 310 a three-armed hook 69 is rotatably journalled on the pin 70. A torsion spring 71 is wound around said pin and tends to rock the hook 69 counterclockwise in Figs. 1 and 5.

Under the action of this spring the back arm 69a of hook 69 engages a pin 72 secured to the intermediate wall 39. In addition, the hook 69 has a bent portion or tab 73 which extends laterally below the projections 74 (Figs. 1 and 13) on the two keys 75 and 76, that is the multiplication or + revolutions key 75 and the division or subtraction key or - revolutions key 76, respectively. These keys are rotatably journalled on a stationary shaft 77 and are acted upon

by individual springs 78 pressing the back end of the key against the stationary guide 31. In addition, these keys have hooks 79 engaging the edges 68 of the rods 28, 29 from above to normally prevent the spring 32 from lifting said rods, that is when the key 75 or 76, respectively, is not depressed. It is to be observed that the key 75 cooperates with the rod 28 and the key 76 with the rod 29. Each key 75 or 76 has a hook 81, which is rockably journaled on a pin 80 on the key and is pressed by a spring 82 to engage the pin 83 on the key. The points 84 of said hooks are somewhat lower than the striking edges 68 of the rods 28, 29, when said rods are in their lowermost position. The keys 75, 76 are integrally formed with the arms 85 and also with the arms 290 or 291, respectively. The arms 85 of said keys engage the pin 331a of an angular piece or contact lever 331 which is pivoted on the stationary pin 333 and controls the electric motor contacts 334. When one of the keys 75 or 76 is depressed, the contact lever 331 is rocked to close the motor contacts 334 starting the motor. The arms 290 and 291 of the keys 75 and 76, respectively, enter in well-known manner a recess in a plus-minus-control plate 287 which is arranged below the base plate of the machine, as shown in Figs. 1 and 5. Reference is made to the corresponding parts 290, 291, 287 in U. S. Patent No. 2,398,286.

A lever 86 (Figs. 1, 4 and 5) is rockably journaled on the stationary pin 87 secured to the frame 88. This lever has four bent tongues or tabs 89, 90, 91 and 92. The tongue 89 (Figs. 1 and 5) extends through a hole in the intermediate wall 39 inwards above the arm 82a of the hook 69. The tongue 90 forms a striking edge for the lever 271 which is pivoted on the stationary pin 325 and with its surface 93 engages the tongue 90. The tongue 91 engages the arm 102 which in well-known manner is acted upon by the tens transfer hook or lever for the totalizer wheel of the highest denomination in the results register. When a ten is carried into that totalizer wheel the arm 102 is swung in the direction of the arrow A in Fig. 5, that is clockwise, as is described in detail for the part 102 in U. S. Patent No. 2,398,286. Finally, the tongue 92 engages the lever 45 (Figs. 1, 5 and 11) to rock that arm, when the lever 86 is swung counter-clockwise. A tension spring 94 presses the arm 86 and its tongue 91 to engage the arm 102.

The rocking or driving lever 267 (Figs. 1 and 5) drives in well-known manner the swing lever 247, and also the plus-minus control plate 287. For details, reference is made to parts 267, 247 and 287 in U. S. Patent No. 2,398,286. The swing lever 247 effects the shifting and the control plate 287 pulls down the keys 75 and 76 during the calculating operations. This control plate 287 is set to its + position and - position by means of the reversal lever 294 in dependence of the setting of the angular piece 36 to which the reversal lever is directly connected. Depending upon how said angular piece and consequently the control plate 287 are set said control plate engages one of the projections 290, 291 of the multiplication key 75 or the division key 76 (as described for the corresponding parts 287, 290, 291 in U. S. Patent No. 2,398,286).

The key holding-down-lever 95 (Figs. 1 and 14) which is rotatably journaled on the stationary pin 96 of the wall 39 has a front bent portion 97 extending inwards through a hole in the in-

termediate wall 39 to engage the bent lower ends 98 (Figs. 1 and 2) of the lifting rods 28 and 29 from above. Said lever 95 has a curved cam slot 99 (Figs. 1 and 14) engaged by the pin 273 secured to a small standard or tongue on the swing lever 247. In addition, a pin 95a (Fig. 11) is riveted to said lever 95 and enters a slot of the contact lever 331 to swing that lever for closing the contacts 334 when the lever 95 is pressed downwards.

The upper end of an impulse arm or lever 100 (Figs. 1 and 11) is displaceably journaled on the pin 53 for the stopping pawls 51 and 52, said impulse lever having an oblong slot through which said pin passes. At its upper end this impulse arm is fork-shaped and has two bent prongs 101 resting on the upper sides of the two pawls 51 and 52. At its lower end this impulse lever carries a pin 103 resting in a slot 104 of the contact lever 331. The slide 241 (Figs. 1, 5 and 15) is controlled by the control lever 201 of the machine as described in U. S. Patent No. 2,398,286 (details 241 and 201 of that patent). The lever 201 serves for setting the machine to multiplication and to division with automatic shifting. Depending upon the setting of this lever the slide 241 is in or out of the path of motion of the hook or pawl 69. When the control lever 201 is in the position *a* or *b* of Fig. 15 (positions of multiplication) the slide 241 is out of the path of motion of the pawl 69, but when the control lever is set to its position *c* for division, the slide 241 enters the path of motion of said pawl.

The release arm 310 (Figs. 1, 11 and 12) acts directly upon the subtraction setting lever 358a (Figs. 1, 11 and 12) of the hook 358. This lever 358a extends outwards through a slot in the casting 105 of the machine. In the embodiment shown the machine has, in addition to the multiplication key 75 and the division key 76 also an addition key, just as in U. S. Patent No. 2,398,286 but no subtraction key; thus, the machine is set to subtraction by pressing the lever 358a downwards to its lowermost position, and when then the division key is depressed, the machine performs an operation of subtraction as described in connection with Fig. 16 of the patent just mentioned. For this purpose the release arm 310 has a striking surface or tongue 310a pressing against the edge or striking surface 378 of the hook 358 when the latter is depressed due to the fact that the operator presses the lever 358a downwards to its lowermost position (for subtraction) or due to the fact that the addition key has been depressed manually. Figs. 1 and 11 show the lever 358a in its uppermost position, while Fig. 12 shows the same in its lowermost position. When the slide 380 is pushed inwards, that is to the right in Figs. 1, 11 and 12, for instance, due to the manipulation of the clearing key 406, the curve or cam 380a of this slide acts on a pin 106 extending through a hole of the intermediate wall 39 and secured to the lever 45. Due to this, the lever 45 is rocked and moves the locking arm 43 (to the left in Fig. 1 and counter-clockwise in Fig. 4) so that the part 42 of that locking arm releases the tongue 41 of the angular piece 36. Under the action of its spring 40, the angular piece 36 with its guiding slot 21a is restored to its neutral, central position so that the coupling pawl 18 is disengaged from the shoulders 20. If the main shaft 58 rotates, when the clearing is started, such rotation is thus stopped, as soon as the current revolution has been completed. The 75 main shaft 58 cannot be started again during the

clearing operation due to the fact that the lever 45 keeps the locking arm 43 rocked aside so that its tongue 42 does not lock the projection 41; consequently the guiding slot 21a and the coupling pawl 18 are restored to their inoperative neutral position, before any of the shoulders 20 come around to the pawl 18, during rotation of the gears 14 and 15. When the slide 380 is displaced to the right in Fig. 11, the pin 412 thereon rocks the arm 411 clockwise in Fig. 11, said arm being pivoted on the pin 333. Consequently, this arm acts on the pin 331a and the contacts 334 are closed for the clearing operation. In clearing operations effected due to the manipulation of the clearing key 406 or when the machine has been set to addition or subtraction and consequently the arm 411 has been swung clockwise in Figs. 1 and 11, the downwardly extending projection 411a of that arm engages the upper side of the bent tongue 269 (Fig. 5) of the lever 271. This prevents all shifting of the actuator during current operations of clearing (also when clearing is effected automatically at the end of an operation of addition or subtraction).

As is described in detail in U. S. Patent No. 2,398,286, the gears 385, 388, 394 (Fig. 1) are driven by the motor M under the control of the coupling arm 392. The clearing key 406 (Fig. 11) is arranged on the link or arm 400 which by means of an oblong slot embraces the stationary pin 400a and also by means of the pin 400b is articulately connected with the lower end of the coupling arm 392, the latter being connected with the slide 380 by means of a spring 408. This slide has a restoring spring 410 and in its backward active position it is locked by a pawl 395 releasable by the pin 397 on the gear 394 after the clearing of the actuator has been finished. A pin 407 is secured to the coupling arm 392 and engages a projection on the slide 380 so that said slide is drawn backwards (to the right in Figs. 1 and 11) when the coupling arm 392 is rocked counter-clockwise for effecting a clearing operation (zeroizing).

A disc 107 (Figs. 3 and 11) is rotatably journaled on the main shaft 58 and carries two pins 108 and 109 which enter the holes 110 or 111, respectively, of the stop discs 56 or 57, respectively, and are guided in said holes. In clearing operations in connection with addition and subtraction, the projection 400c (Fig. 11) of the rod 400 is moved to engage the periphery of the disc 107 when the slide 380 is moved to the right in Fig. 11 and by means of the spring 408 tends to rock the coupling arm 392 counter-clockwise, said coupling arm being articulately connected with the rod 400. This prevents any clearing operation from being started as long as the main shaft 58 rotates. Similarly, the projection 400c engages the periphery of the disc 107, when the clearing key 406 is depressed manually for initiating a clearing operation and this prevents the clearing operation from beginning as long as the main shaft rotates. Not until after said shaft has been stopped in its full cycle position by the stop pawls 51 and 52, does the spring 408 pull the projection 400c into the recess 107a of the disc 107, and this swings the coupling arm 392 counter-clockwise so that the clearing is effected. Thus, said disc 107 is stopped and locked, but nevertheless the main shaft 58 may move slightly beyond its position of rest while compressing the buffer spring 59; for instance, in an operation of addition the disc 57 may move somewhat counter-clockwise, because the pin 109 can move somewhat in the hole 111.

Thus, the discs 56 and 57 are rocked during a short moment, while the actuator R and the main shaft 58 are stopped and their kinetic energy is absorbed by the buffer spring 59.

MODE OF OPERATION

For the various kinds of operation, the device described acts as follows:

Multiplication

The control lever 201 is set to its position *a* or *b* in Fig. 15, thus causing the slide 241 controlled thereby to be moved out of the path of motion of the hook 69 (Figs. 1 and 5). At this setting, 15 the plus-minus-control plate 287 is locked, as described in detail in U. S. Patent No. 2,398,286, and it is consequently not moved by the eccentric-driven lever 261 in its rocking motion.

After the multiplicand has been entered in the 20 actuator R (Fig. 16) in well-known manner, the multiplication key 75 (Fig. 1) is depressed, causing the arm 85 of that key to rock the contact lever 331 clockwise in Fig. 1 in such manner that the electric contacts 334 for the motor M are

closed. When the motor starts, the swinging arm 23 (Figs. 1 and 4) is rocked by the cam discs 25 and 26. When the operator depresses the key 75, its oblique edge or hook 79 (Fig. 1) releases the edge 69 of the coupling rod 28 so that said 30 rod is free and displaced upwards by its spring 32. Then, the upper part of this rod enters the recess 27 (Figs. 1 and 2) of the rocking arm 23 and consequently, the lifted rod 28 is moved by the rocking arm 23 so that said rod is displaced laterally to the left in Fig. 2. During this operation, the pin 34 on the rod acts upon the angular piece 36 causing that piece to be displaced to the left in Fig. 2 and consequently the guiding slot 21a (Fig. 7) rocks the coupling pawl 18 in the 35 same direction, that is upwards in Fig. 16. The projection 42 of the locking arm 43 (Figs. 2 and 4) then engages the bent pawl 41 of the angular piece 36, so that the spring 40 (Fig. 7) cannot restore said angular piece to its neutral central position.

40 When the angular piece 36 is displaced in the manner just described, the pin 48 secured thereto follows and is moved to the left in Fig. 6 to act upon the conical pins 49, 50 so that they are pressed apart and thus the stopping pawls

45 51, 52 are lifted from the shoulders 54, 55 on the buffer discs 56 and 57, respectively. The main shaft 58 is now released from the stopping pawls and begins rotating in a + revolution. When the 50 pawls 51, 52 are lifted, they themselves lift the 55 impulse arm 100.

When the pawl 18 is swung upwardly as described above (see Fig. 16) said pawl becomes coupled to the shoulder 20 on the gear 15. This 60 couples the main shaft 58 with the motor to be driven thereby in + revolutions, that is, counter-clockwise in Fig. 1.

When the cam slot disc 62 (Figs. 1 and 8) secured to the shaft 58 begins moving, its eccentric slot 64 forces the release arm 310 to be rocked 65 clockwise in Figs. 1 and 11, said release arm engaging the slot 64 by means of a roller 65. The horizontal arm 66 of the release arm 310 then is lowered towards the striking edge 68 (Figs. 1 and 2) on the coupling rod 28 and thus presses said

70 rod (and also the rod 29) downwards to its lowermost position, which is somewhat lower than its position of rest shown in Fig. 1.

The key 75 still remains depressed, and consequently the hook 81 (Figs. 1 and 13) on that key 75 is pressed inwardly by the spring 82 to engage

the coupling rod 28 and the oblique surface of the point 84 of that hook now snaps in above the edge 68 of the coupling rod 28, to keep said rod in its lowermost position after the moment at which the arm 66 of the release arm 310 begins to move counterclockwise under the action of the eccentric cam slot 64.

When the multiplication key 75 is kept depressed, its striking surface 74 (Figs. 1 and 13) is in the path of motion of the bent portion 73 of the hook 69, when said hook is rocked by the release arm 310 at the rocking motion of said arm as just mentioned. The arm 69a of the hook 69 then is disengaged from the stationary pin 72 and the arm 69a slides freely along the tongue 89 of the lever 86 (see position e of the hook 69 in Fig. 5) during its reciprocating motion so that said last-mentioned lever is not actuated. But if the key 75 returns to its position of rest (non-depressed position), the striking surface 74 is moved out of the path of motion of the tongue 73 of the hook 69. Under the action of the torsion spring 71, the arm 69a is then pressed upwards against the pin 72 and slides along said pin during its motion and with its point strikes the tongue 89 of the lever 86, as shown in the position f of the hook 69 in Fig. 5, in which the position d is the position of rest of that hook. This swings said arm 86 counterclockwise in Fig. 5 so that its tongue 92 strikes the arm 45 and rocks it counterclockwise in Fig. 1, that is to the left in Fig. 4. The locking arm 43 follows in that motion and its part 42 is moved out of the path of motion of the part 41 of the angular piece 36 which now is restored to its inoperative central position by the spring 40 (Fig. 7). This restores the pin 48 secured to that angular piece to its central position shown in Fig. 6 and the stopping pawls are released; their torsion spring 501 now presses them downwards against the periphery of the buffer discs 56, 57. During its continued rotation the coupling pawl 18 is acted upon by the oblique surface 21b of the guide member 21 (Fig. 7), now in its central position, and consequently this pawl is drawn out of its engagement with the shoulder 20 of the gear 15 (Fig. 16) so that the main shaft 58 is disconnected from the motor. When the stopping projections 54, 55 of the buffer discs 56 or 57, respectively, are just in front of the points of the stopping pawls 51, 52, the torsion spring 501 presses these stopping pawls into engagement with said stop projections 54, 55. Because the main shaft 58 is rotating in + revolutions, that is counter-clockwise in Fig. 1, the stop projection 54 strikes the stop pawl 51. The kinetic energy of the rotating actuator R on the main shaft 58 is absorbed by the buffer spring 59 so that the rotating parts are softly and safely stopped. It is to be observed that during the whole bouncing action, the stopping pawls 52, 51 engage the stopping projections 55, 54 permanently and without any relative motion. This means that there is no risk that the stopping pawls will swing out and be disconnected, but on the contrary, the rotation is rapidly and reliably stopped. It is to be observed that, for example in a + revolution, the stop pawl 51 may be depressed to its lowermost stopping position almost one half revolution before the main shaft 58 is stopped. As is shown in Fig. 10, the disc 56 has substantially the shape of a half circle and permits the stopping pawl 51 to swing down to its stopping position approximately one-half revolution (of the main shaft 58) in advance. When

then the stopping projection 54 strikes the stopping pawl 51, the disc 57 continues rotating somewhat counter-clockwise, so that the pawl 52 can easily be rocked down against the projection 55.

When in the manner just described the lever 86 is rocked counter-clockwise in Figs. 1 and 5 under the action of the hook 69, also the lever 271 is released from the tongue 90 and is lifted upwards by its spring. This releases in well-known manner (see U. S. Patent No. 2,398,286) a shifting impulse, because the pawl 265 (Fig. 5) is thus released and enters the path of motion of the driving lever 267, which then drives the swinging lever 247 carrying the pawl 265 with which the step-shifting mechanism of the actuator may be coupled. When thus the swinging lever 247 begins moving (to the left in Fig. 5) the pin 273 secured to said lever acts upon the arm 271 and presses it downwards in Fig. 5 so that the tongue 90 of the lever 86 again engages the surface 93 and locks the arm 271 in its lowermost position shown in Fig. 5. During this operation, said pin 273 moves in the slot 99 (Figs. 1 and 14) of the key depresser or key holding-down member 95, which is consequently depressed so that its bent portion 97 presses the bent lower ends 98 of the coupling rods 28, 29 downwards. Consequently, said rods cannot be released and cannot be lifted upwards to engage the rocking lever 23. Thus, the main shaft 58 and consequently also the actuator R cannot be started, as long as a shifting operation is being carried out.

When the multiplication key 75 returns to its position of rest, the contact lever 331 is still kept in its operative position and keeps the contacts 334 closed, because the pin 103 of the impulse lever 100 (Figs. 1 and 11) presses on the contact lever, said impulse lever being now raised to its uppermost position by the lifted stop pawls 51, 52. The electric contacts 334 hence remain closed until the pawls 51 and 52 pivot downwardly to engage the projections 54 and 55, and thus move the arm 100 downwardly to open the contacts. However, before this occurs the pawls have arrested the main shaft 58 and the actuator R in full cycle position. This is very important for a rapid and reliable action of the machine.

Division

For division the control lever 201 is set manually to its right position at c in Fig. 15. Thus, the slide 241 is moved into the path of motion of the hook 69 (Figs. 1 and 5). As is described in detail in U. S. Patent No. 2,398,286, the plus-minus-control plate 287 is now free and can be displaced, when a shifting impulse arrives.

The dividend is entered in well-known manner into the actuator R and is transferred to the results register. The actuator (and, if necessary, also the revolutions counter) is cleared and then the divisor is entered into the actuator, which is now in the usual manner tabulated to its extreme left position, that is to the highest decimal denominations of the results register. To start the machine the operator now depresses the division key 76 which actuates the contact lever 331 and closes the electric contacts 334. In a manner analogous with that described above under the heading "Multiplication," the coupling rod 29 is lifted and the main shaft 58 is started to rotate clockwise in Fig. 1, that is in a - revolution.

When the cam slot disc 62 rocks the release arm 310, the hook 69 (Fig. 5) follows and with its edge engages and slides on the slide 241, as

shown at *e* in Fig. 5. The slide 241 thus prevents the hook 69 from moving to its effective position *f* after the division key 76 has been restored to its position of rest. In other words, the hook 69 will not act upon the part 89 of the lever 86. Said lever thus remains unactuated and the main shaft 58 with the actuator R continues rotating in — revolutions until the capacity of the results register is exceeded and, consequently, a ten is carried from the highest denomination of that register. This swings the arm 102 in the direction of the arrow A in Fig. 5 and this motion is transferred to the lever 86 which is consequently swung counter-clockwise. As described above under the heading "Multiplication" this causes the striking surface 92 to swing the arm 45 (Figs. 1 and 4) and consequently the locking arm 43. Hence, the angular piece 36 is now free and it is restored to its inoperative, central position so that the main shaft 58 is disengaged from the motor and the actuator R is resiliently stopped by the stopping pawls 51 and 52.

When the lever 86 in the manner just described is rocked counter-clockwise in Figs. 1 and 5 under the action of an impulse from the arm 102 at the tens transfer, also the arm 271 is released from the tongue 90 and this releases in well-known manner (U. S. Patent No. 2,398,286) a shifting impulse, because the pawl 265 is released and springs out into the path of motion of the driving lever 267. Consequently said lever now drives the swinging lever 247 carrying the pawl 265 to shift the actuator one step. When the angle piece 36 is moved to its outermost position (— position) it acted in well-known manner on the plus-minus-coupling arm 294, and said arm then sets the control plate 287 to pull down the multiplication key 75 via its projection 298. The driving lever 267 by means of the plus-minus-driving lever 274 acts on the control plate 287 to displace it and to cause it to pull down the multiplication key 75.

Then, the automatic division is continued in well-known manner.

Addition

When the item (addend) has been set in the actuator R in well-known manner, the actuator, upon the depression of the addition key, performs one single + revolution in the manner described above under the heading "Multiplication" and is stopped. Then the actuator is automatically cleared in the manner described in U. S. Patent No. 2,398,286 due to the fact that the slide 380 is displaced to the right in Fig. 11, when the hook 358 is moved downwards (counter-clockwise) at the depression of the addition key.

Subtraction

Subtraction is carried out similarly as an operation of addition. The subtrahend is set in the actuator R, the setting lever 358a for subtraction is moved downwards by the operator and the division key 76 is depressed. Now the actuator performs a — revolution, is stopped and automatically cleared.

What we claim is:

1. In a power operated calculating machine, in combination, multiplication and division keys independent of each other, an actuator, an electric motor, a coupling under the control of said keys for coupling said motor to said actuator for rotating the latter in either direction selectively, lifting rods for controlling said coupling, lifting springs for said rods, said rods being nor-

mally locked in their lower position by said keys against the lifting action of said springs, a restoring lever driven by said motor, and a projection on said restoring lever for restoring said lifting rods to their lower positions.

2. In a power operated calculating machine having an actuator rotatable in two directions under the control of a multiplication key and a division key and also having a step shifting mechanism for said actuator for shifting it rectilinearly in either direction, in combination, normally ineffective cyclically driven means for operating said shift mechanism, a cam disc connected for rotation in synchronism with said actuator, a follower engaging said cam disc, and an impulse hook journalled on said follower and under the control of said keys for rendering said normally ineffective means effective, said hook cooperating with said keys to be disabled thereby when depressed and reenabled when released.
3. In a power operated calculating machine having an actuator rotatable in two directions under the control of a multiplication key and a division key and also having an impulse operated step shifting mechanism for the relative denominational shifting of said actuator rectilinearly in two opposite directions, a cyclically operated driving lever and a normally uncoupled swing lever operable by the driving lever to operate said shifting mechanism, in combination, an impulse giving member under the direct control of said keys operative to couple said swing lever to said driving lever, said member cooperating with said keys to be rendered inoperative to give a releasing impulse for coupling the swing lever to the driving lever when one of said keys is depressed but again rendered operative to give an impulse to couple said swing lever to the driving lever when said depressed key is released, and power operated means for automatically reciprocating said release impulse giving member through its impulse giving motion at every rotary operation of the actuator.

4. In a power operated calculating machine having an actuator rotatable in two directions under the control of a multiplication key and a division key and also having an impulse operated step shifting mechanism for the relative denominational shifting of said actuator rectilinearly in two opposite directions, a cyclically operated driving lever and a normally uncoupled swing lever adapted to be driven by the driving lever to operate said shifting mechanism, in combination, a releasing member under the direct control of said keys operative to couple said swing lever to said driving lever, said member cooperating with said keys to be rendered inoperative to effect coupling of said swing lever to said driving lever for providing an impulse to said step shifting mechanism when one of said keys is depressed but again rendered operative to effect coupling of the swing lever to the driving lever to provide an impulse to said shifting mechanism when said depressed key is released, power operated means for automatically reciprocating said releasing member at every rotary operation of the actuator, and a full cycle mechanism for stopping the rotation of said actuator, said full cycle mechanism being actuated by said releasing member when said depressed key is released from its depressed position.
5. In a power operated calculating machine having an actuator rotatable in two directions under the control of a multiplication key and a division key and also having a step shifting

- 70
- 75

mechanism for said actuator for shifting it rectilinearly in either direction, a cyclically operated driving lever and a normally uncoupled swing lever adapted to be coupled to and driven by the driving lever to operate said shifting mechanism, in combination, a full cycle mechanism for stopping the rotation of said actuator, a cyclically operable releasing member cooperating with and under the direct control of said keys so as to be rendered effective upon release of a depressed key, a lever rockable by said releasing member, when effective, to couple said swing lever to said driving lever, a motor, a coupling adapted to couple said actuator to said motor for rotation in either direction, lifting rods under the control of said multiplication and division keys for controlling said coupling, a guide member for said coupling and said lifting rods, a locking device for said guide member and thus for said coupling, and an arm rockable to release said locking device and to render said full cycle mechanism operative, said arm being in the path of said lever and being operated thereby when the lever is rocked by said releasing member.

6. In a power operated calculating machine having an actuator rotatable in two directions under the control of a multiplication key and a division key, and also having a step shifting mechanism for said actuator for shifting it rectilinearly in either direction, in combination, a motor, a pair of rotatable members, gearing between said motor and said members for driving the latter in opposite directions of rotation, clutch means for connecting said actuator to either of said members, lifting rods, one rod being associated with each key, a lifting spring urging each of said

rods from a normal position, said rods being restrained by said keys against the urge of said springs and adapted under the urge of said springs to cause adjustment of said clutch means for positive or negative rotation of said actuator according to which of said keys is depressed, each said key having a fixed striking surface for locking the associated rod against the urge of its spring as long as its associated key is in normal undepressed position, cyclically operated means for restoring said lifting rods to normal position, and a locking hook pivoted on each said key to keep the associated lifting rod locked in its normal position, as long as the associated key remains depressed.
